CIRCUIT BREAKER WITH IMPROVED
RESET MEANS

Frank B. Desio, Melrose Park, and John F. Marquis,
St. Charles, Ill., assignors to Littelfuse, Incorporated,
Des Plaines, Ill., a corporation of Illinois
Filed Feb. 6, 1961, Ser. No. 37,430
6 Claims. (Cl. 200—113)

This invention relates to circuit breakers of the thermostatic type having a "trip free" manual reset feature and, which also may serve as an "on" and "off" manual switch. More specifically it has reference to a circuit breaker of the type aforesaid which is fool-proof against deliberate manual closure of the circuit during overload of a value causing automatic opening, but which allows reset upon subsidence of the overload current to a safe or "continuous rating" value.

The principal object of the invention is to provide a device adapted to carry a normal or so-called "continuous rating" current but which will open automatically upon passage of current of a value in excess of normal and which will remain in open condition until manually reset, i.e. reclosed, the reset means being so arranged that the device cannot be manually held in the closed position if the overload condition persists but will continue to remain open. However upon cessation of overload the switch may be manually reset.

Another object resides in a resetting actuator or button for the purpose aforesaid which may also be employed to open the circuit manually and to maintain the same open until shifted to "on," whereupon the automatic functioning of the device as a circuit breaker is resumed.

Other objects and advantages will become apparent from the ensuing description which, taken with the accompanying drawing, discloses a preferred mode of carrying the invention into practice.

In this drawing:

FIG. 1 is a perspective view of a device embodying the invention, as assembled for use;

FIG. 2 is a cross section, somewhat enlarged, taken on the line 2—2 of FIG. 1;

FIG. 3 is a cross section taken on the line 3—3 of FIG. 2;

FIG. 4 is a cross section taken on the line 4—4 of FIG. 2;

FIG. 5 is a detail in perspective of the spring associated with the reset button to bias the same normally to "off" condition of the switch;

FIG. 6 is a detail in perspective of the reset button minus the spring of FIG. 5; and

FIG. 7 is a detail in perspective of the base of the device and its thereto secured movable switch member and associated fixed contact.

Broadly regarded, the invention circuit breaker comprises a base mounting a pair of terminals to connect the device in the circuit. To one terminal is secured a temperature-controlled switch element, e.g. of the bimetallic type, responsive to the value of the current through the switch whereby normal value thereof permits the element to maintain a normal position engaging a fixed contact but which, when subjected to a temperature corresponding to some value of current beyond the rated maximum, will disengage the fixed contact and open the circuit, and which, upon reduction in current, i.e. temperature, will reengage the fixed contact and reclose the circuit automatically. If, upon reclosure, the overload condition has been alleviated the contacts will remain closed whereas, if such is not the case, the switch element will re-open the same, and such re-cycling will continue until the overload condition is relieved or the switch is manually re-opened by actuation of the reset

2

actuator to "off." The switch element is made sufficiently wider than the contact button carried thereby for cooperation with shoulders on the reset actuator or may be provided with lateral projections for the same purpose.

5 The reset actuator is rendered shiftable in suitable guides whereby the shoulders aforesaid may, alternatively, take up a first position precluding deliberate reclosing of the contacts which have been opened in response to an overload until the overload has been relieved, or a second position in which the switch is placed in "off" condition. Such shoulders are each provided with a ramp which, when the switch blade is heated by overload and opens, enter under the blade thereby preventing recycling of the element and reclosing of the contacts. If, during overload, the reset actuator is manually shifted to "on," i.e. reset position, the switch blade will continue to recycle. A spring associated with the reset actuator constantly urges the same toward the position at which the shoulders will underlie the switch blade so that, if the reset actuator, once moved to "on," is released during the overload, the switch blade is prevented from closing the contacts. Upon cessation of overload the switch may be reset by shifting the reset actuator to "on." If the switch is to be opened manually irrespective of an overload condition, the reset actuator is shifted to "off," whereat the shoulders enter under the laterally-projecting sides of the switch blade to withhold the same positively from closing pending subsequent manual restoration of the actuator to "on."

30 Adverting now to the drawing, we have shown, by way of example, a combined automatic circuit breaker and manual switch embodying the principles of the invention. There is shown a base 10 of electrically insulating material having an essentially flat top surface 11 for a purpose to appear, and a peripheral recess 12 to frictionally receive a box-like cover 13, which fit may be implemented by any well-known means, e.g. a detent arrangement.

35 40 Carried in the base 10, as by integrally molding the same therein, are terminal posts 15 and 16 extending below the base in threaded ends for attachment of any suitable form of electrical terminals whereby the device may be connected in the circuit to be protected or interrupted. Desirably, the posts 15 and 16 are knurled at 19 and 20 and suitably shouldered as shown to insure permanence, as is well known. At its inner end the post 15 has a switch blade or element 22 secured thereto as by providing a hole in the blade fitted over a reduced portion of the post and over which latter a washer 23 is placed, the end of the post being upset. If desired, said reduced end may be in the nature of a spline receiving a complementary hole in the switch blade for more reliable lateral positioning thereof.

50 55 The switch blade 22 is shown as of substantially flat-sided, oval contour and is associated with or incorporates means which will cause the blade to flex about its fixed end in response to the rise in temperature concomitant upon increase in current. One desirable form thereof is a bimetal slightly dished over its extent in order to obtain snap action when the contacts are opened, sometimes termed "oil-can" action by analogy to the function of the base of a conventional squirt type of oil can. The normal bias to which the switch blade is subjected is in a direction maintaining the device closed. The desired heating effect results when the contacts are closed and overload current flows through the blade. The desired snap action may be improved by providing a hole 25 in the center. Other forms of switch blade may be availed of provided that laterally extending portions are presented for co-action with the shoulder portions or cams of the reset actuator shortly to be detailed. For example the switch

blade may be a generally elongated member provided adjacent its distal end with a pair of laterally extending wings for such coaction.

The free end of the blade 22 is provided with a conventional contact button 31. Such contact is adapted for circuit closing and opening action with respect to a similar fixed contact button 32 borne on the upper end of the terminal post 16. In the example, the geometry of the assembly is such that a cavity 33 is formed in the base 10 providing clearance for the contacts 31 and 32.

From the foregoing it will have become apparent that, during flow of rated current the contacts will remain closed by virtue of the bias applied to the blade 22 and that, upon passage of overload current, the blade will flex or be deflected to open the contacts whereupon the temperature responsive means cools and attempts to re-establish the circuit. The arrangement whereby the movable contact is prevented from actually touching the fixed contact pending manual reset will be described herein-after. If, at the time reset is attempted, the overload has not been relieved the switch will repeat such abortive opening and closing action until the reset actuator is moved to "OFF" position, as will appear.

The "reset" and "off" actuator 40 is best illustrated in FIG. 6 and it comprises a member of electrically insulating material guided for longitudinal shifting movement with respect to the base 10, i.e. from right to left and vice versa as seen in FIG. 2. The actuator comprises a top wall 41 with depending side walls 42-42 slidable on the flat top surface 11 of the base 10 receiving, between them, the blade 22 and being guided by the interior of the side walls of the cover 13 (FIG. 3). Sliding, vertical fit with respect to the flat top 11 of the base and the interior of the top wall of the cover 13 is obtained by suitable choice of the height of the actuator, e.g. the distance between a pad 46 thereon and the bottom edge of the walls 42-42 (FIG. 2).

The pad 46 bears the indicia "ON" and "OFF" arranged to be exposed alternatively in a window 51 in the top of the cover 13 through which an operating finger 52 protrudes for access.

The actuator 40 is constantly subject to leftward bias ("off" position) under the urging of a spring member 61 (FIG. 5) of somewhat box-like form having a top wall 62 apertured at 63 to fit snugly over the pad 46, a notch 64 to define a bridge 65 underlying an extended part 66 of the pad 46 and a partial right wall 67 abutting the right-hand face of the actuator whereby the spring member is lodged in operative relation with the actuator. The height of the pad 46 is only slightly greater than the thickness of the spring member and the pad has minimum clearance with the cover 13. Thus, the latter affords further retention. It will be noted that the several clearances are exaggerated in FIGS. 2 and 3 for clarity of comprehension. The partial end wall 67 continues as a cantilevered leaf spring 71 bearing against the adjacent end wall of the cover 13.

The lateral walls 42-42 of the actuator are each provided with a projection or shoulder 73 having a substantially horizontal face 73a and an inclined face 73b adapted to enter beneath the switch blade 22.

The operation will now be described. Assuming the switch is in its "on" position, the actuator 40 being to the right (full lines in FIG. 2), the surfaces 73a and 73b are engaged by the edge of the distal end of the switch blade 22. Parenthetically it is to be noted that, while the full line showing of FIG. 2 might indicate interference there is actually none by reason of the quadrantal corners of the distal end of the blade 22. In this position of the actuator the resiliency of the blade closes the contacts and the circuit is completed and also holds the actuator in the "on" position. Upon occurrence of overload, the blade opens the circuit and will undertake to recycle the opening and closing operations. However, upon opening action, the leaf spring 71 urges the actuator 40 to the left to

project the surfaces 73a under the blade 22 (broken lines A in FIG. 2). Thus, the blade will be held open until the switch is manually reset by operation of the actuator to the right, withdrawing the surfaces 73a and freeing the blade 22.

If the overload is persistent and the operator attempts to restore the circuit by deliberately holding the actuator "on," the blade 22 will simply continue to recycle until the current has been reduced to the rated value, whereafter the function is as described above.

To turn the switch off, the actuator 40 is manually pushed to the left or "off" position, forcing the surfaces 73a under the blade 22. Entry of the surfaces 73a beneath the blade is facilitated by the leading, inclined surfaces 73b.

From the foregoing it will have become clear that the invention comprehends a circuit-interrupting device which will protect against some predetermined maximum value of current and which will remain in the open condition until manually reclosed following decline of overload current to a safe value. Otherwise expressed, during recycling action in the presence of overload current, the device cannot be deliberately held closed. Also, manual opening of the switch is also provided.

While we have shown a particular embodiment of our invention, it will be understood, of course, that we do not wish to be limited thereto since many modifications may be made and we, therefore, contemplate by the appended claims to cover any such modification as falls within the true spirit and scope of our invention.

We claim:

1. A combination switch and circuit breaker adapted to interrupt an electrical circuit upon manual manipulation or upon an excess current flow in the electrical circuit comprising, an electrical insulating base, a fixed contact mounted on said base, a resilient bimetallic switch blade mounted on said base and adapted to engage and disengage the fixed contact, means connecting said fixed contact and blade in the circuit for controlling the current flow therethrough, said blade normally resiliently engaging the fixed contact to close the circuit but being movable upon excess current flow in the circuit to disengage the fixed contact to open the circuit, an actuator guided for shifting movement on said base and shiftable between "on" and "off" positions, a projection on the actuator having a first surface for engaging and maintaining the blade out of engagement with the fixed contact when the actuator is in its "off" position, spring means for biasing the actuator to its "off" position, a handle on the actuator for shifting the actuator to its "on" position against the action of the spring means to allow the blade to engage the fixed contact, said projection on the actuator having an inclined second surface merging with the first surface and engaging the blade when the blade is engaging the fixed contact for maintaining the actuator in its "on" position against the action of the spring means, said inclined second surface on said projection engaging the blade and said spring means biasing the actuator to its "off" position operating to aid in disengaging the blade from the fixed contact upon excess current flow in the circuit, and said inclined second surface on said projection engaging the blade and said actuator when manually moved by said handle to its "off" position operating manually to disengage the blade from the fixed contact regardless of the current flow in the circuit.

2. A circuit breaker adapted to interrupt an electrical circuit upon an excess current flow therein comprising, an electrical insulating base, a fixed contact mounted on said base, a resilient bimetallic switch blade mounted on said base and adapted to engage and disengage the fixed contact, means connecting said fixed contact and blade in the circuit for controlling the current flow therethrough, said blade normally resiliently engaging the fixed contact to close the circuit but being movable upon excess current flow in the circuit to disengage the fixed contact to open

the circuit, an actuator guided for shifting movement on said base and shiftable between "on" and "off" positions, said shiftable actuator including end walls and a face therebetween and a pad protruding from the face, a metallic member having a flat part overlying the face of the actuator with the aperture closely fitting said pad and a part engaging at least one end wall of the actuator to locate said member relative to the shiftable actuator, a portion of said metallic member being struck out therefrom to constitute a cantilever leaf spring means for engaging a fixed part associated with the base for biasing the actuator to its "off" position, a projection on the actuator having a first surface for engaging and maintaining the blade out of engagement with the fixed contact when the actuator is in its "off" position, a handle extending from the pad on the actuator for shifting the actuator to its "on" position against the action of the spring means to allow the free end of the blade to engage the fixed contact, said projection on the actuator having a second surface merging with the first surface and engaging the blade when the blade is engaging the fixed contact for maintaining the actuator in its "on" position against the action of the spring means.

3. A combination switch and circuit breaker adapted to interrupt an electrical circuit upon manual manipulation or upon an excess current flow in the electrical circuit comprising, an electrical insulating base, a fixed contact mounted on said base, a resilient bimetallic switch blade mounted on said base and adapted to engage and disengage the fixed contact, means connecting said fixed contact and blade in the circuit for controlling the current flow therethrough, said blade normally resiliently engaging the fixed contact to close the circuit but being movable upon excess current flow in the circuit to disengage the fixed contact to open the circuit, an actuator guided for shifting movement on said base and shiftable between "on" and "off" positions, said shiftable actuator including end walls and a face therebetween and a pad protruding from the face, a metallic member having a flat part overlying the face of the actuator with the aperture closely fitting said pad and a part engaging at least one end wall of the actuator to locate said member relative to the shiftable actuator, a portion of said metallic member being struck out therefrom to constitute a cantilever leaf spring means for engaging a fixed part associated with the base for biasing the actuator to its "off" position, a projection on the actuator having a first surface for engaging and maintaining the blade out of engagement with the fixed contact when the actuator is in its "off" position, a handle on the actuator for shifting the actuator to its "on" position against the action of the spring means to allow the blade to engage the fixed contact, said projection on the actuator having an inclined second surface merging with the first surface and engaging the blade when the blade is engaging the fixed contact for maintaining the actuator in its "on" position against the action of the spring means, said inclined second surface on said projection engaging the blade and said spring means biasing the actuator to its "off" position operating to aid in disengaging the blade from the fixed contact upon excess current flow in the circuit, and said inclined second surface on said projection engaging the blade and said actuator when manually moved by said handle to its "off" position operating manually to disengage the blade from the fixed contact regardless of the current flow in the circuit.

4. A combination switch and circuit breaker adapted to interrupt an electrical circuit upon manual manipulation or upon an excess current flow in the electrical circuit comprising, an electrical insulating base, a fixed contact mounted on said base, a resilient bimetallic switch blade mounted at one end on said base and having its free end engaging and disengaging the fixed contact, means connecting said fixed contact and blade in the circuit for controlling the current flow therethrough, said

blade normally resiliently engaging the fixed contact to close the circuit but being movable upon excess current flow in the circuit to disengage the fixed contact to open the circuit, an actuator guided for shifting movement on said base and shiftable between "on" and "off" positions, a projection on the actuator having a first surface for engaging and maintaining the free end of the blade out of engagement with the fixed contact when the actuator is in its "off" position, spring means for biasing the actuator to its "off" position, a handle on the actuator for shifting the actuator to its "on" position against the action of the spring means to allow the free end of the blade to engage the fixed contact, said projection on the actuator having an inclined second surface merging with the first surface and engaging the free end of the blade when the blade is engaging the fixed contact for maintaining the actuator in its "on" position against the action of the spring means, said inclined second surface on said projection engaging the free end of the blade and said spring means biasing the actuator to its "off" position operating to aid in disengaging the blade from the fixed contact upon excess current flow in the circuit, and said inclined surface on said projection engaging the free end of the blade and said actuator when manually moved by said handle to its "off" position operating manually to disengage the blade from the fixed contact regardless of the current flow in the circuit.

5. A circuit breaker adapted to interrupt an electrical circuit upon an excess current flow therein comprising, an electrical insulating base, a fixed contact mounted on said base, a resilient bimetallic switch blade mounted at one end on said base and having its free end engaging and disengaging the fixed contact, means connecting said fixed contact and blade in the circuit for controlling the current flow therethrough, said blade normally resiliently engaging the fixed contact to close the circuit but being movable upon excess current flow in the circuit to disengage the fixed contact to open the circuit, an actuator guided for shifting movement on said base and shiftable between "on" and "off" positions, said shiftable actuator including end walls and a face therebetween and a pad protruding from the face, a metallic member having a flat part overlying the face of the actuator with the aperture closely fitting said pad and a part engaging at least one end wall of the actuator to locate said member relative to the shiftable actuator, a portion of said metallic member being struck out therefrom to constitute a cantilever leaf spring means for engaging a fixed part associated with the base for biasing the actuator to its "off" position, a projection on the actuator having a first surface for engaging and maintaining the free end of the blade out of engagement with the fixed contact when the actuator is in its "off" position, a handle on the actuator having a second surface merging with the first surface and engaging the free end of the blade when the blade is engaging the fixed contact for maintaining the actuator in its "on" position against the action of the spring means to allow the free end of the blade to engage the fixed contact, said projection on the actuator having an inclined second surface merging with the first surface and engaging the free end of the blade when the blade is engaging the fixed contact for maintaining the actuator in its "on" position against the action of the spring means to allow the free end of the blade to engage the fixed contact, said projection on the actuator having a second surface merging with the first surface and engaging the free end of the blade when the blade is engaging the fixed contact for maintaining the actuator in its "on" position against the action of the spring means.

6. A combination switch and circuit breaker adapted to interrupt an electrical circuit upon manual manipulation or upon an excess current flow in the electrical circuit comprising, an electrical insulating base, a fixed contact mounted on said base, a resilient bimetallic switch blade mounted at one end on said base and having its free end engaging and disengaging the fixed contact, means connecting said fixed contact and blade in the circuit for controlling the current flow therethrough, said blade normally resiliently engaging the fixed contact to close the circuit but being movable upon excess current flow in the circuit to disengage the fixed contact to open the circuit, an actuator guided for shifting movement on said base and shiftable between "on" and "off" positions,

said shiftable actuator including end walls and a face therebetween and a pad protruding from the face, a metallic member having a flat part overlying the face of the actuator with the aperture closely fitting said pad and a part engaging at least one end wall of the actuator to locate said member relative to the shiftable actuator, a portion of said metallic member being struck out therefrom to constitute a cantilever leaf spring means for engaging a fixed part associated with the base for biasing the actuator to its "off" position, a projection on the actuator having a first surface for engaging and maintaining the free end of the blade out of engagement with the fixed contact when the actuator is in its "off" position, a handle extending from the pad on the actuator for shifting the actuator to its "on" position against the action of the spring means to allow the free end of the blade to engage the fixed contact, said projection on the actuator having an inclined second surface merging with the first surface and engaging the free end of the blade when the blade is engaging the fixed contact for maintaining the

actuator in its "on" position against the action of the spring means, said inclined second surface on said projection engaging the free end of the blade and said spring means biasing the actuator to its "off" position operating to aid in disengaging the blade from the fixed contact upon excess current flow in the circuit, and said inclined second surface on said projection engaging the free end of the blade and said actuator when manually moved by said handle to its "off" position operating manually to disengage the blade from the fixed contact regardless of the current flow in the circuit.
